[57] CLAIM

The ornamental design for a vehicle instrument panel, as shown and described.

DESCRIPTION

FIG. 1 is a front elevation view of a vehicle instrument panel showing our new design;

FIG. 2 is a top plan view thereof, the bottom being a mirror image of that shown; and

FIG. 3 is a side elevation view thereof, the opposite side being a mirror image of that shown.

The rear of the vehicle instrument panel is substantially flat and unornamented.

FIG. 1

FIG. 2

FIG. 3
